UNITED STATES PATENT OFFICE.

LLOYD A. WIEDERSTEIN, OF CINCINNATI, OHIO.

HEADREST SUPPORTING AND ADJUSTING APPARATUS.

Application filed September 19, 1924. Serial No. 738,676.

My invention relates to improvements in chair back and head rest supporting and adjusting apparatus. One of its objects is to provide an improved head-rest supporting and adjusting apparatus applied to a chair back. Another object is to provide for applying a head-rest apparatus to a chair back, having an enameled metal frame in which is mounted an upholstered chair back center. 10 Another object is to provide a combined chair back and head-rest supporting and adjusting apparatus. Another object is to provide in connection with a chair back an improved headrest supporting and adjusting apparatus. Another object is to provide in connection with a chair back an improved headrest supporting and adjusting apparatus adapted to be constructed chiefly from stamped metal members. My invention also 20 comprises certain details of form and combination and arrangement of components, all of which will be fully set forth in the description of the accompanying drawings, in which:

25 Fig. 1 is a front elevation of a chair back and head-rest apparatus embodying my invention.

Fig. 2 is a rear elevation of the same partly in section.

30 Fig. 3 is a perspective view of one of the head-rest supporting members detached.

Fig. 4 is a perspective view of another head-rest supporting member detached.

Fig. 5 is a perspective view of a releasing 35 push button detached.

Fig. 6 is a perspective view of a coiled spring employed to oppose the push button.

Fig. 7 is a detail of a portion of the chair back frame.

40 Fig. 8 is a detail of a portion of the upholstering frame.

The accompanying drawings illustrate the preferred embodiment of my invention in which 15 represents an annular metal chair back frame of angular cross section, which is designed to be enamel finished. An upholstering frame 16 preferably of wood is first provided at its front face with an upholstering pad 17 faced with leather or similar upholstering material. The rear face of

the frame 16 is also provided with an irregular shaped recess 18 to receive the shank 19 of a head-rest 20, and to receive the head-rest supporting and adjusting members to be carried by the chair back, before the upholstering frame 16 is introduced into the chair back frame 15 and secured thereto. 55

The head-rest supporting and adjusting members comprise a plate 22 provided at opposite ends with inwardly directed projections 24 and 26, having perforations 27 and 28 therein to serve as vertical guides for the shank 19 of a head-rest. I preferably provide a shank having polygonal faces, and corresponding polygonal faced recesses 65 to thereby prevent the shank from moving rotatably within the recesses 27 and 28. The plate is secured over the rear face of the wider portion of the recess 18 and is rigidly secured in place by means of screws passed through perforations in the ears 29 at the four corners of the plate 22 and into the frame 16. The plate 22 is also provided with a tongue 30 projecting partly into the recess 18 and to which a latch or locking member 32 is pivotally attached substantially midway thereof. 70

The latch member 32 is provided with a polygonal recess 34 through which the shank 19 of the head rest passes, and in which said shank has a relatively close sliding fit when the latch member lies in a substantially horizontal plane. When the latch member 32 is canted or tilted into a substantially inclined plane the latch member 32 acts to lock the 75 shank 19 against movement endwise relative to the chair back.

At the opposite end of the latch member 32 from the recess 34 is a pin or stud 36 which enters the upper end of a coiled spring 37, which is seated in a cylindrical portion 38 of the recess 18, to thereby normally tilt the latch member 32 upwardly into an inclined position within the recess 18. A push button 40 is seated above the 90 latch member 32 opposite the stud 36 and spring 37 in a branch 42 of the recess 18 with the upper end of the push button projecting through a perforation 44 in the top of the frame 15 and extending above the 95 100

top of the frame 15. A collar 46 on the push button limits the upward movement of the push button. The shank 19 of the head-rest passes through a perforation 48 in the top of the frame at one side of the perforation 44 to enter the recess 18. The spring 37 normally holds the latch member 32 in an inclined position to latch the shank 19 to the plate 22 and to the chair back, and at 10 the same time serves to normally hold the push button in its elevated position.

When it is desired to release the shank 19 from the plate 22 for the purpose of detaching the head-rest from the chair back, or to 15 secure a higher or lower position of adjustment for the head-rest relative to the chair back, the operator pushes the push button 40 downwardly against the action of the spring 37 with one hand while with the other hand 20 he either adjusts or removes the head-rest. As soon as pressure on the push button 40 is released the latch member 32 automatically returns to an inclined position to latch the head-rest to its new position of adjustment, which it retains until the push button 25 is again depressed.

A piece of upholstering material is fitted over the rear face of the frame 16 to conceal the plate 22 and recess 18 previously 30 to fitting the frame 16 into the frame 15. The shank 19 may be cylindrical instead of polygonal if desired. The plate 22 and latch member 32 are both adapted to be constructed by stamping from sheet metal, 35 whereby uniformity of parts, uniformity and reliability of strength, and relatively light weight of parts is insured. My improved head-rest support lends itself to convenient assembly and operation in connection with a metal chair back frame, and 40 is compact and adapted to be entirely housed within the upholstering frame with the exception of the head of the push button.

The apparatus herein shown and described 45 is capable of considerable modification within the scope of the claims without departing from the spirit of my invention.

What I claim is:

1. Head-rest supporting and adjusting apparatus comprising a chair-back upholstering frame provided with a housing recess open at the top, an annular metal frame encircling said upholstering frame and closing the open end of said housing recess, said annular frame being provided with a perforation for the passage of a head-rest shank and with a push-button perforation, a shank guiding plate attached over the rear face of said housing recess and provided 50 with recesses to receive and guide a head-rest shank vertically, a latch member pivotally mounted in said recess and provided at one end with a perforation to receive the head rest shank, a member to normally hold 55 said latch member in an inclined position,
- and a push-button located in said housing recess with its head projecting through said annular metal frame and adapted to be actuated from the exterior of said annular frame to shift said latch member into position to release the head-rest shank. 70
2. Head-rest supporting and adjusting apparatus comprising a chair back frame, a housing recess in said frame to receive a head-rest shank and shank engaging means, 75 a supporting plate spanning said recess and provided with inwardly directed projections at opposite ends having perforations to receive and guide said shank endwise of said shank, a latch member pivotally attached to 80 an ear at one side of said supporting plate and provided with a recess to receive said shank and adjustable to lock said shank to said plate, means to yieldingly hold said latch member in an inclined position to lock 85 said shank to said plate, and a push-button operable from the top edge of the exterior of said frame to engage and shift said latch member temporarily to a position to release said shank from said plate. 90
3. Head-rest supporting and adjusting apparatus comprising a chair back frame, a housing recess in said frame to receive a head-rest shank and shank engaging means, 95 a stamped sheet metal shank supporting plate spanning and closing the rear face of said housing recess and provided at top and bottom with inwardly turned projections provided with perforations to receive and guide said shank endwise of said shank and with a laterally located inwardly extending projection adapted to pivotally support a latch member, a latch member pivotally attached at an intermediate point to said laterally located projection and provided at 100 one end with a shank receiving perforation substantially in alignment with said shank supporting and guiding perforations and adapted to adjustably lock said shank to said plate, means to yieldingly engage said 110 latch member tending to hold said latch member normally in an inclined position to lock said shank to said plate, and a push-button projecting from the edge of the chair back frame and adapted to engage said latch 115 member to release said shank from its locked relation to said plate. 120
4. Head-rest supporting and adjusting apparatus comprising a chair-back upholstering frame provided with a housing recess open at the top, an annular metal frame of angular cross-section encircling said upholstering frame and serving to close the upper end of said housing recess and provided with a perforation for the passage of a head-rest shank into said recess and a perforation for the passage of the head of a push-button from said recess to the exterior of said metal frame, a shank guiding member located in said recess and serving to 125 130

support and guide the shank of the head-rest endwise of said shank, a resiliently actuated latch member located in said housing recess and serving to normally latch the 5 head-rest shank to said chair-back frame, and a push-button projecting from the top edge of said chair-back frame through a

perforation in said annular metal frame and operable from the exterior of said frame to temporarily release said latch member from 10 said head-rest shank.

In testimony whereof I have hereunto affixed my signature.

LLOYD A. WIEDERSTEIN.
